Primary Examiner—Ian Simmons*Assistant Examiner*—Christopher Lee(74) *Attorney, Agent, or Firm*—Wood, Herron & Evans, LLP(57) **CLAIM**

The ornamental design for a tube retainer, as shown and described.

DESCRIPTION

FIG. 1 is a perspective view of a tube retainer incorporating the design of our invention;

FIG. 2 is a front elevational view thereof;

FIG. 3 is a left side elevational view thereof, the right side view being a mirror image thereof; and,

FIG. 4 is a top plan view thereof.

The features of the tube retainer shown in phantom lines are not elements of the design of our invention.
